Claims priority, application Germany Aug. 31, 1955

8 Claims. (Cl. 102—39)

This invention relates to a blank cartridge with a bullet-shaped head pushed on to the metal cartridge case but intended to be retained thereon when the cartridge is fired.

One object of the invention is to attach the bullet-shaped head to the case in a simple way and in such a manner that it will not be blown off when the cartridge is fired.

A further object of the invention is to construct the blank cartridge in such a way that inaccurately sized cases produced in the manufacture of live ammunition (rejected cases) as well as spent cartridge cases of fired live ammunition can be used for making blank cartridges.

Another object of the invention is to enable fired blank cartridge cases to be re-used. This means that the bullet-shaped head should not only be suitably attached to the cartridge case to prevent it from being blown off when the cartridge is fired but that its removal from the case after the latter has been fired and ejected from the fire-arm should be easily possible. At the same time there should be no difficulty in attaching a fresh bullet-shaped head to a fired cartridge case without the case being deformed by the removal of the old head and its replacement by a new one. Any deformation that might occur in effecting such a replacement could impair the mechanical strength of the cartridge case and hence also affect the reliability with which the new bullet-shaped head was retained.

Yet another object of the present invention consists in giving the blank cartridge a shape, powder charge, and performance that will make it fit for use in automatic fire-arms.

A further object of the invention consists in fashioning the blank cartridge in such a way that, apart from cardboard, the bullet-shaped head may be made of an elastic plastic material and be so designed that any reduction in its elasticity and mechanical strength under the influence of heat and cold will not in any way affect the reliability with which the head is held when the cartridge is fired.

A further object of the invention consists in providing sufficient space inside the cartridge case for a powder charge that will produce the necessary volume of gas for the actuation of automatic fire-arms without however creating an undesirably high gas pressure.

Another object of the invention is to provide a bullet-shaped head that can be cheaply manufactured, a matter of particular importance when making the head of a plastic material.

Another object of the invention consists in ensuring that the fired and extracted blank cartridge in a machine gun or automatic fire-arm will be properly ejected and not cause the fire-arm to jam by being caught in front of the returning bolt after recoil. It is therefore a more particular object of the invention to provide a blank cartridge which in weight corresponds so far as possible with a live cartridge and in which the centre of gravity of the extracted part of the cartridge is located as nearly as

2

possible in the same place as in the case of an extracted live cartridge case.

A further object of the invention is to make the blank cartridge resistant to deformation in the region of the shoulder and of the approximately cylindrical neck.

Other objects of the invention will be readily understood with reference to the following description and drawings.

The invention consists in that the bullet-shaped head which externally embraces the forward cylindrical neck of the cartridge case is provided with a cone-shaped annular skirt which bears against the shoulder of the cartridge case and which in the loaded fire-arm fills or is compressed within the space between the shoulder of the cartridge case and the wall of the chamber at the rear end of the barrel.

The specific advantage inherent in this arrangement is the fact that the said skirt in the loaded fire-arm is located in the gap between the shoulder of the cartridge case and the walls of the chamber.

The skirt is compressed into this space more particularly when the cartridge is fired. Its compression is due to the pressure created inside the cartridge case by the combustion of the powder forcing the metal walls of the case outwards on to the walls of the chamber and thereby firmly wedging the skirt between the cartridge and the chamber walls. At the same time the pressure of the powder gases inside the cylindrical neck of the case acting in the direction of the barrel walls has the effect of compressing that section of the bullet-shaped head which adjoins the skirt, and of thereby assisting in retaining the bullet-shaped head on the case. The skirt which embraces the shoulder of the cartridge case and the section of the bullet-shaped head which bears against the cylindrical neck of the cartridge case are not directly exposed to the flash and the heat of the gases so that the firing of the blank will not raise their temperature sufficiently to impair their mechanical strength.

At the same time the cartridge can be readily inserted into the chamber and the case can be easily extracted. Moreover, the bullet-shaped head can be easily removed from the fired case after extraction either by pulling or tearing it off. Plastic heads can be melted off and cardboard heads or the like can be boiled off if required.

Further details of the invention will be described with reference to the illustrative examples shown in the drawings in which

Fig. 1 is a blank cartridge according to the invention shown in side the chamber of a fire-arm and drawn on an enlarged scale;

Fig. 2 is an enlarged representation of a detail of the blank cartridge according to Fig. 1;

Fig. 3 is another form of construction of a blank cartridge according to the invention, and

Fig. 4 is a detail of another form of construction similar to that shown in Fig. 3, the two latter drawings being on a different scale to the first.

The blank cartridge 1 shown in Figs. 1 and 2, with which a fire-arm is assumed to have been loaded, comprises a metal case 2 with a tapering portion 2a which fits into the correspondingly shaped chamber 3 at the rear end of the barrel 4. At the end of the tapering portion 2a facing the barrel is a shoulder 5. The cartridge case 2 then extends to form a cylindrical neck 6. An outwardly projecting ring 7 is worked into the cylindrical neck 6. Two grooves 8 are recessed into the neck, one on either side of the projecting ring. Pushed over the cylindrical neck 6 is a bullet-shaped head 6 which is extended to form a slightly cone-shaped tubular skirt 10 bearing against the shoulder 5. That part of the bullet-shaped head 9 which embraces the roughly cylindrical neck 6 of the cartridge case 1 is internally grooved for

engaging the annular projection 7 and it also carries two projections which engage the grooves 8.

Further forward the bullet-shaped head is provided with a shoulder 11 which does not, however, when the fire-arm is loaded make close contact with the shoulder 12 at the junction of the chamber and the barrel 4. When the cartridge is inserted into the chamber the outer wall 13 of the lip 10 of the skirt bearing against the shoulder of the case 2 abuts the angle 14 in the corresponding part of the chamber. The bullet-shaped head has a suitably rounded nose 15 and is provided on its inside with a number of notches, the disposition of for instance four such notches 16 being shown in the drawing of the enlarged section illustrated in Fig. 2.

The bullet-shaped head 15 contains a plug 17 made of felt or the like, and a suitable quantity by weight of powder to provide a charge 18 is contained in the powder chamber of the case 2.

The blank cartridge functions as follows:

When the blank cartridge is fired the expanding powder gases enter the cavity inside the plastic bullet head 17 and drive the plug 11 through the nose which tears out towards the nozzle. The powder gases press the cartridge case 1 radially outwards on to the walls of the chamber. Consequently the plastic part of the bullet-shaped head which embraces the cartridge case is tightly compressed between the cartridge case and the chamber walls. The bullet-shaped head is thereby effectively prevented from being blown out of the barrel.

A modified form of construction of the blank cartridge is illustrated in Fig. 3 and shows the walls of the tapering part 50 of the case which forms the powder chamber thickened towards the base of the cartridge. The base 20 of the cartridge is fitted with a cap, not shown, and is provided with channels which communicate with the interior of the cartridge. It also has a bevel edge 21 and an annular groove 22 above the said edge, the bottom of the groove being perpendicular with reference to the base whereas the upper edge 23 of the same is likewise bevelled. The tapering portion 50 of the cartridge case is modified towards the head of the cartridge to form a shoulder 24 surmounted by a cylindrical neck 25. An outwardly projecting annular beading 26 is embossed into the cylindrical neck 25, the lower lateral edge 27 of which is perpendicular with reference to the longitudinal axis of the cartridge. The edges 27 of the beading are rounded. Below the shoulder 24 a felt plug 29 is inserted into the interior of the case. Below the felt plug 29 is the powder charge 40.

A bullet-shaped head 30 is pushed on to the case as shown in Fig. 3. The bullet-shaped head 30 is provided with a cone-shaped skirt 31 which bears on the shoulder 24 whereas its lower extremity 32 is butt ended. The outer surface 33 of the tapering skirt 31 fits against a shoulder inside the chamber when the cartridge is loaded into the breech. Above the skirt 31 the bullet-shaped head has an annular step 34. The mouth 35 of the cartridge case is located beyond this step.

The bullet-shaped head 30 is of uniform wall thickness extending from the step 34 upwardly as far as a zone 36. Above this annular zone 36 the bullet-shaped head is domed 37 and its wall thickness decreases. Notches 38 are cut into the inside of the dome 37. The presence of the notches 38 produces a very thin wall section in the nose 39 of the head. The bullet-shaped head 30 is retained on the case, on the one hand, by the beading 26 and on the other hand by the cone-shaped skirt which is pressed between the shoulder of the case and the corresponding angle in the chamber at the end of the barrel when the cartridge is ready for firing.

When a fire-arm is loaded with the blank cartridge the tapering portion 50 of the case is in contact with the chamber walls and the base 20 of the cartridge abuts the bolt with the extractor engaging the groove 22. The outside surface 33 of the skirt 31 is in contact with the

shoulder in the chamber wall and the outer surface of the bullet-shaped head is in contact with the walls of the barrel up to the annular zone 36. The powder gases released by the charge 40 when the cartridge is fired drive the felt plug 29 through the cavity inside the cylindrical collar 25 of the case and into the interior of the bullet-shaped head 30. Owing to the pressure generated inside the case the tapering portion 50, the shoulder 24, and the roughly cylindrical neck 25 are pushed outwards, and the wall of the tapering portion 50 is firmly pressed against the chamber walls. The shoulder 24 presses the skirt 31 into the corresponding angle in the chamber wall whereas the adjacent section of the bullet-shaped head between the mouth 35 of the cartridge case and the shoulder 24 is firmly wedged between the roughly cylindrical neck 25 and the corresponding part of the barrel wall. The beading 26 is pushed into the cooperating groove in the bullet-shaped head. The cooperation of these parts produces a gastight joint and holds the bullet-shaped head sufficiently tightly to prevent it from being blown off. The gas pressure inside the cartridge case drives the plug 29 further upwards against the notches 38 which then tear open roughly from the nose 39 of the head to approximately the annular zone 38, so that the plug is propelled into the barrel without blowing off the bullet-shaped head 30. The torn ends of the nose 38 are flattened against the inside walls of the barrel.

Fig. 4 illustrates a particularly simple method of attaching the bullet-shaped head. In a modification of the form of construction illustrated in Fig. 3 the cylindrical neck 41 of the cartridge case lacks an annular groove or an annular beading and no corresponding projection or groove is provided in the bullet-shaped head. The bullet-shaped head 42 shown in Fig. 4 and its cone-shaped skirt 43 are attached to the cartridge case 1 by means of an adhesive between the bullet-shaped head 42, the neck 41, and the shoulder 24. Otherwise case and head are of similar shape to that shown in Fig. 3.

The blank cartridge shown in Fig. 4 functions as has been hereinabove already described. The bullet-shaped head is retained in position on the cartridge case, substantially as has been explained in connection with the preceding forms of construction, by means of the cone-shaped skirt 43 wedged between the shoulder 24 and the corresponding internal angle in the chamber at the rear end of the barrel.

The bullet-shaped head described in the illustrative examples shown in Figs. 1 to 4 may consist of a soft or a hard synthetic plastic material such as polythene, polyvinyl chloride, or of cardboard, asbestos, plexiglass, vulcanised fibre, or the like. An elastic synthetic is preferable as this easily tears when the cartridge is fired and is readily deflected against the barrel walls owing to its elasticity.

The cartridge case may be brass, tombac (72-90% copper, remainder zinc), steel, plated steel, copper, or the like.

It will be readily understood that the cartridge as well as the bullet-shaped head may also have some other shape to conform with the construction of the fire-arm and that the invention must not be deemed as being in any way limited by the illustrative examples that have been described.

Moreover the felt plug may be inserted in some other position than that shown in Figs. 1 to 3. A preferred position is that illustrated in Fig. 3.

The bullet-shaped head (9, 30, 42) may also consist of metal, especially light metal such as aluminium or aluminium alloy. In this case the depth of the grooves 8 or the height of the annular beading 26 has to be smaller than shown in Fig. 1 and 3.

What I claim is:

1. A blank cartridge for a fire-arm comprising a barrel, a cartridge chamber located at the rear end of the barrel and having a frusto-conical shoulder portion at the rear

of said chamber; said cartridge comprising a metal cartridge case having a forward cylindrical neck, a frusto-conical shoulder located immediately behind the neck, and a sleeve-like body located behind the shoulder, a charge of powder located within the sleeve-like body, a bullet-shaped head comprising a weakened closed end, a skirt covering the forward cylindrical neck of the cartridge case and a frusto-conical extension of the skirt covering the shoulder of the cartridge case, the skirt and extension being arranged when loaded into the fire-arm to substantially fill the space within the cartridge chamber and frusto-conical portion thereof and external to the neck and shoulder of the cartridge respectively, while the bullet-shaped head projects into the barrel of the fire-arm, whereby upon discharge of the blank cartridge the pressure of the gases arising from the powder charge causes the shoulder and neck on the cartridge case to expand and to hold fast the extension of the skirt and the skirt itself against the frusto-conical shoulder portion of the cartridge chamber and the cartridge chamber respectively, while the closed end of the bullet-shaped head bursts and liberates the gases into the barrel of the fire-arm and hence into the atmosphere.

2. The combination claimed in claim 1, for use with a fire-arm having a second shoulder located at the entrance to the barrel forwardly of the frusto-conical shoulder portion, wherein the skirt of the bullet-shaped head is provided with a stepped portion adapted to substantially abut said second shoulder when the blank cartridge is loaded into the fire-arm.

3. The combination claimed in claim 1, wherein the

skirt of the bullet-shaped head and the extension thereof are secured respectively to the neck and frusto-conical shoulder of the cartridge case by adhesive means.

5. The combination claimed in claim 1 wherein the cylindrical neck of the cartridge case is provided with an external annular beading, and wherein the bullet-shaped head is provided with an internal recessed groove corresponding and engaged with said beading.

10. The combination claimed in claim 1 wherein the lower end of said frusto-conical extension is provided with a butt-ended annular vertical surface.

15. The combination claimed in claim 1 further comprising a felt plug located forward of the charge in the sleeve-like body of the cartridge case.

15. The combination claimed in claim 4, wherein the surface of the beading which faces the base of the cartridge is normal to the axis of the sleeve-like body.

20. The combination claimed in claim 4, wherein the section of the annular beading has rounded corners.
